UNITED STATES PATENT OFFICE.

EDGAR A. JACKSON, OF CUPERTINO, CALIFORNIA.

NURSERY-TREE DIGGER.

1,302,051.

Specification of Letters Patent. Patented Apr. 29, 1919.

Application filed December 28, 1916. Serial No. 268,299.

To all whom it may concern:

Be it known that I, EDGAR A. JACKSON, a citizen of the United States, and a resident of Cupertino, in the county of Santa Clara and State of California, have invented certain new and useful Improvements in Nursery-Tree Diggers, of which the following is a specification.

My invention relates to a nursery tree digger in which a movable power unit is anchored in alinement with a row of trees and utilized to operate a cutting element whereby the said trees forming the row may be removed from the ground rapidly, effectively and without injury thereto.

One object of my invention is to provide a device of the character indicated which includes means for effecting a uniform pull upon both sides of the cutting element; which is provided with means for effecting lateral or angular movement of the device with small expenditure of power; which provides an arrangement of power transmitting elements whereby the mechanism for shifting the device and the mechanism for operating the cutting element may be operated independently of or in conjunction with each other as desired. A still further object of my invention is to provide a device of the character indicated that is so constructed as to be readily anchored in position, and that will be simple in operation and cheap to manufacture.

With these and other objects in view, the invention consists in the novel and useful provision, formation, construction, combination and relative arrangement of parts, members and features all as hereinafter described, shown in the drawings and finally pointed out in the claims.

In the drawings:

Figure 1 is a plan view of my invention with portions of the shifting mechanism and cutting mechanism removed.

Fig. 2 is a side elevation of the invention as shown in Fig. 1.

Fig. 3 is a sectional view on line 3—3 of Fig. 1.

Fig. 4 is an illustrative plan view of my invention anchored in position with the mechanism set for the positioning of the cutter.

Fig. 5 is an illustrative plan view of my invention anchored in position with the cutting mechanism in operation.

Fig. 6 is an illustration showing the op-

eration of the mechanism used for shifting the device.

Similar characters of reference indicate similar parts throughout the several views. 60

Referring now more particularly to the drawings, 1—1 indicates a pair of parallelly spaced beams supported upon transversely positioned runners 2—2 provided with shoes 3—3. Upon beams 1—1 is positioned a suitable motor 4 and transversely positioned shafts 5 and 7 operating in bearings 6—6 and 8—8 respectively. Shaft 5 is operated by motor 4 through the medium of drive-shaft 9 connected to fly-wheel 10 by a suitable clutch as 10^a operated by lever 11, and shaft 7 is operated by shaft 5 through the medium of gears 12 and 13. Shaft 7 also carries a terminal gipsy-spool 14 for the purpose hereinafter specified. 75

An additional shaft 15 is mounted on beams 1—1 parallel with shaft 7 and operates in bearings 16—16, and carries a gear 17 fixedly secured near one end thereof. On shaft 7 is slidably mounted a gear 18 operating on a feather 19 and thrown into and out of mesh with gear 17 by a lever 20 pivotally mounted on beam 2. Shaft 15 also carries a pair of drums 21 and 22 revolvably mounted thereon and provided with bevel gears 23 and 24 respectively, which gears are in mesh with pinions 25—25—25 revolvably mounted in plate 26 which is in turn fixedly mounted on shaft 15, thereby providing a differential whereby an equal pull is transmitted to cables 27 and 28 attached to their respective drums. Attached to the outer ends of cables 27 and 28 is a cutter 29 designed to be drawn under the root systems of a row of nursery trees and thereby cut 95 the said trees loose from the ground.

In operating the cutter 29 the device above described is anchored in alinement with a row of trees in any suitable manner as by firmly embedding in the ground a pair 100 of posts as 30—30 and placing a beam 31 so as to engage the same. A cable 32 is attached to the forward end of the device and a chain 33 is secured to cable 32 and beam 31. The gear 18 is now thrown out of mesh with gear 17 as indicated in Fig. 4 whereby the cables 27 and 28 may be unwound and the cutter 29 properly positioned without operating any of the mechanisms connected to shaft 7. When the cutter 29 is in position, the gear 18 is thrown into mesh with gear 17 and the clutch 10^a thrown into an 110

operative position thereby causing the cables 27 and 28 to wind up evenly on drums 21 and 22 as indicated in Fig. 4, the clutch 10^a being disengaged again when the last 5 tree has been removed.

If the device is to be moved laterally to a new position in alinement with an adjacent row of trees, then gear 18 is thrown out of engagement with gear 17 and gipsy-spool 10 on shaft 7 only is operated at will by the engagement or disengagement of clutch 10^a with fly-wheel 10. A pulley-block 34 is attached to the drum end of one beam 1 and an angle bar 35 is attached to the opposite end of the same beam 1, the angle bar being provided with a plurality of holes 36. A cable 37 is now hooked to a central hole 36 then passed through pulley-block 38, thence through pulley-block 34 and around gipsy-spool 14. The pulley-block 38 is secured by cable 39 to a fixed post not shown. The clutch 10^a now being thrown into an operative position the cable 37 is pulled in by the operation of spool 14 and the whole 25 device moved laterally into a new position. If for any reason it is desired to move the device at an oblique angle, as when an obstruction 40 is encountered, then the cable 37 is attached to an inwardly positioned 30 hole as 36^b in Fig. 6, and the desired angular movement is secured. The outwardly positioned holes 36^b permit adjustments for angular movement in the opposite direction.

35 The specific form of supporting structure shown and described is considered necessary and so claimed because the cables 27 and 28 must be operated close to the ground in order to secure proper action of the cutter.

40 It is desired that the drum operating mechanism and the mechanism for shifting the device laterally be capable of simultaneous operation because in practice it is

usually desirable to first position the device as shown in dotted lines at 41 and then 4 when the cutter is put into operation to operate the said shifting mechanism until the exact required alinement is secured.

I claim:

1. A nursery tree digger comprising a 50 pair of parallel, spaced runners, a pair of parallel, spaced supporting beams mounted thereon and at right angles thereto, a motor mounted on said beams, a driving-shaft having a clutch therein operatively mounted 55 with respect to said motor, three horizontal parallel shafts revolvably mounted on said beams at right angles to said driving shaft, fixed gear connections between the driving shaft and the first of said parallel shafts, 60 fixed gear connections between the first and second of said parallel shafts, a gipsy-spool mounted on one end of the second of said parallel shafts, disengageable gear connections between the second and third of said 65 parallel shafts, a pair of cable operating drums revolvably mounted on said third parallel shaft, a differential drive connecting said drums to said last mentioned shaft, and adjustable means operated through the medium of said gipsy-spool and its driving mechanism for moving said device.

2. A nursery tree digger as claimed in claim 1 in which the adjustable means for moving the device comprises a cable operated by 75 said gipsy-spool and its driving mechanism, a pulley-block engaging said cable and attached to one of said beams adjacent said gipsy-spool, an external anchorage for said cable and means for adjustably attaching 80 said cable to said beam at the end opposite to the said gipsy-spool.

In testimony whereof I have hereunto affixed my signature this 18th day of December, 1918.

EDGAR A. JACKSON.
